UNITED STATES PATENT OFFICE.

FRED HIRSH, OF NEW YORK, N. Y., ASSIGNOR TO ADJUSTA COMPANY, OF NEW YORK, N. Y., A CORPORATION OF NEW YORK.

SLIDE FASTENER.

Refile for application Serial No. 128,964, filed August 13, 1926, abandoned November 4, 1928. This application filed December 11, 1928. Serial No. 325,374.

This application has been filed in place of abandoned application Number 128,964, filed August 13, 1926.

This invention relates to a fastening device for women's undergarments, and more particularly to a slide fastener by which to adjustably and detachably secure to such articles of feminine apparel as brassières, banteaux, and the like, the ends of the shoulder straps by which they are supported.

The present day requirements demand a fastening which is neat in appearance, is inconspicuous, and will not only provide for the suitable adjustment of the straps, but also will permit of a ready removal for laundering or for the replacement of one set of straps by another of a color in harmony with the color of the outer garment worn therewith.

I have supplied this want by providing for the purpose a slide fastener which is extremely small and light, and which, while permitting of ready adjustment and replacement, will securely hold in place a strap of the sheer, smooth silk ribbon now used—a thing which no other fastener with which I am familiar will do.

The invention will be understood by reference to the accompanying drawing, in which—

Figure 1 is a view showing in perspective a garment equipped with my new fastenings; Figs. 2, 3 and 4 are views respectively showing the slide on a somewhat enlarged scale in plan, in section, and as attached to a garment; Fig. 5 is a plan view of a slightly modified form of slide; and Fig. 6 is a similar view of a portion of a garment with slide and the end of a strap secured therein.

As illustrated, *a* indicates the garment, or portion thereof, *b* indicates a strap, and *c* indicates a fastener. The integral slide, of thin metal preferably rustless, has a plurality of very narrow slots *d*, an intermediate bar or bars *e*, and two outer bars *f* each of which is bent upon the slide at substantially right angles to the plane thereof so that the inner side portions of the two outer bars are in substantial alignment with the outer edges of the end slots. The outer bar thus serves both as the usual outer bar and as an in-turned clamping lip, which lip, owing to the

narrowness of the slots, could not be formed of metal stamped therefrom.

In its preferred form, the slide is provided with three slots and is attached to the garment by sewing thereto—on a bar-tacking sewing machine, for example,—the bar between the middle and the lower slot, as shown in Fig. 4, thus permitting the upper portion of the slide to be tilted outwardly, and thereby facilitating the threading of the strap end through the slots, and also increasing the clamping effect of the upper lip. By reason of the sharp bends produced therein by the narrow slots and the perpendicular lips and the clamping effect of the latter, a strap of the sheerest and smoothest silk ribbon will be securely held in the position to which it is adjusted.

What I claim as new, and desire to secure by Letters Patent, is—

1. A slide fastener of the character described having a thin metallic body cut out to provide a plurality of transverse bars and intermediate narrow slots and having its two outer bars bent upon the body substantially at right angles to the plane thereof, the inner side portions of the two outer bars being in substantial alignment with the outer edges of the end slots.

2. A slide fastener of the character described having a thin metallic body cut out to provide three narrow transverse slots and four transverse bars and having the two outer bars bent upon the body substantially at right angles to the plane thereof, the inner side portions of the two outer bars being in substantial alignment with the outer edges of the end slots.

3. A slide fastener to receive and adjustably hold one end of a light strap consisting of a thin metallic body cut out to provide three narrow transverse slots and four transverse bars, the outer bar adjoining the slot through which the end of the strap is first to be passed being bent upon the body substantially at right angles to the plane thereof and with its inner portion in substantial alignment with the outer edge of the slot and the slide secured to the part to which the strap is to be attached along the intermediate bar adjoining the other outer bar.

FRED HIRSH.
